UNITED STATES PATENT OFFICE.

EDSON O. SESSIONS, OF CHICAGO, ILLINOIS.

HIGH-TENSION SUSPENSION-INSULATOR.

1,248,559.

Specification of Letters Patent.

Patented Dec. 4, 1917.

Application filed July 10, 1916. Serial No. 108,301.

To all whom it may concern:

Be it known that I, EDSON O. SESSIONS, a citizen of the United States, residing at Chicago, in the county of Cook and State of Illinois, have invented a certain new and useful Improvement in High-Tension Suspension-Insulators, of which the following is a specification.

My invention relates to an improved construction of high tension insulators in which a plurality of insulating units is employed and connected together in a series so that the insulating value of the device as a whole is substantially the sum of the insulating values of the units employed in the construction.

My invention pertains particularly to suspension insulators of the kind referred to employed for insulating antenna for high tension wireless work and line wires carrying extremely high voltage currents. My invention is characterized by improved devices for connecting the insulating units together which devices are mechanically clamped to the insulators without the use of cement so that the difficulties heretofore experienced with cement connections such as disintegration and break-down, due to mechanical strains and high frequency impacts, are avoided. The mechanical connecting devices are provided with flexible connections so that the units of the complete insulators may move somewhat, relatively to each other which is extremely desirable for insulators of this kind on account of the swaying of the supported wires. In using insulators of this kind large strains are brought to bear upon the connections employed between the insulator units particularly in high power wireless installations having antenna of great length, and my mechanical clamp connections much more effectively stand these strains than is possible with cement connections.

A further feature of my invention consists of having insulating units of different size in the complete insulator, the smaller of the insulating units being at the conductor supporting end of the insulator while the larger of the insulating units are at the ground end of the complete insulator which results in bringing the electrostatic field to the ground

end of the complete insulator, thereby saving fatiguing and aging of the insulator units due to corona effect, brush discharge and high frequency impacts. This arrangement of insulator units also provides a better dielectric for a system of suspension units. In practice I find it desirable to have one or more insulating units of large size at the ground end of the device, then one or more units of smaller size and so on throughout the complete insulator, the smallest insulator unit or units being located at the conductor supporting end of the system of suspension units. In other words the insulator units taper from large to small size from the ground end of the suspension system to the conductor supporting end thereof.

My invention is shown in its preferred embodiment in the accompanying drawings in which—

Figure 1 shows in side elevation a complete assembly of suspension units for antenna work,

Fig. 2 shows in diagrammatic view the arrangement of two suspension systems for supporting an antenna,

Fig. 3 shows in a diagrammatic view an arrangement of a suspension system for supporting a high tension electric conductor,

Fig. 4 shows in plan view on an enlarged scale one of the insulating units with its clamping device attached,

Fig. 5 shows a central sectional view taken along the line 5—5 in Fig. 4 the parts shown in Fig. 4, and also a portion of the next insulating unit and the mechanical connections employed between the two units,

Fig. 6 shows in transverse sectional view taken along the line 6—6 in Fig. 5 the construction of the mechanical clamp engaging the upper portion of the upper insulating unit shown in Fig. 5,

Fig. 7 shows in a view similar to Fig. 5 the insulating unit adjacent the conductor supporting end of the suspension system employed for antenna work together with the conductor supporting devices carried by said unit,

Fig. 8 is a sectional view of the parts shown in Fig. 7 taken along the line 8—8,

Fig. 9 is a sectional view of a clamping device for supporting from the last insulator

unit a high tension electric line conductor, and

Fig. 10 shows in perspective view a form of saddle support for a high tension electric line conductor which may be used in connection with the supporting clamp shown in Fig. 9.

Similar numerals refer to similar parts throughout the several views.

10 The suspension system of units shown in Fig. 1 consists of a first set of insulating units 15 of relatively large size, a second set of insulating units 16 of somewhat smaller size, a third set of insulating units 17 of still 15 smaller size and a fourth set of insulating units 18 of still smaller size, the last one of the insulating units 18 serving to support the devices by which the antenna is supported.

20 The insulating units referred to are connected together by similar mechanical clamping devices 19 and 20 in series arrangement so that the dielectric strength of the suspension system is substantially equal to 25 the added dielectric strength of the several insulator units. The clamping element 20 connected to the end unit 15 engages a supporting ring 21 by which the suspension system may be secured to any desired support as 30 for example by the wire 22 shown in Fig. 2 to the upper end of a tower 23. The clamping element 19^c connecting with the end unit 18 is provided with devices to be described for receiving the end of the antenna 24 to 35 support the same in substantially the position shown in Fig. 2. When it is borne in mind that the antenna used in connection with some of the high power wireless stations must be of large length, in some cases 40 over 1000 feet, and that the permissible sag of the antenna is small, and that the antenna is subjected to very high voltages, in some cases several hundred thousand volts, it will be understood that the mechanical construction of the suspension system must be of 45 great strength and of high and permanent insulating value, and it is a purpose of the present invention to effectively meet both of these requirements together with others to 50 be noted which are peculiarly incident to high tension work especially when high frequency currents flow through the conductors supported by the suspension systems.

As shown in Figs. 4, 5 and 6 each insulator unit consists of a flanged body portion 55 15^a affording a large insulating surface, and from opposite sides of said body portion projecting bosses 15^b and 15^c extend provided with enlarged heads having transverse 60 grooves formed through their outer surfaces, these grooves being at substantially right angles to each other for receiving the bolts of the clamping devices. Each complete 65 clamping device consists as stated of a member 19 and a member 20, which mem-

bers are of the same construction the only difference being in the position of the members when in engagement with each other. It will, therefore, be necessary to describe but one of these members, as for example 70 the member 20, which consists of two sections 20^a and 20^b which together form a cup for surrounding the boss 15^b. The edge of the cup thus formed is provided with an in-turned bead entering the circular groove 75 formed inside of the enlarged head of the boss 15^b, a strip of somewhat compressible insulating material 25 being inserted between the bead and the boss to compensate for slight irregularities in the clamp or in 80 the insulator. The insulating material used may be mica or oiled silk or some other similar material for affording the bead of the clamp a positive clamping engagement in the groove of the boss 15^b. The halves 20^a 85 and 20^b of the cup are held in place by a screw 26 extending through bosses formed in the inside of the cup in the ends of the transverse groove through the projecting boss 15^b of the insulator. The sections 20^a 90 and 20^b have projecting from the outer surface thereof hooks 27 and 28 which over-lap each other at their end portions as shown at 27^a and 28^a, the overlapping portions being of reduced thickness so that the total thickness 95 of the hook portions is substantially uniform throughout, these hook portions being in line with each other and extending along a diameter of the cup. The hook portions are so disposed and are of such a shape 100 that they together form an opening or hole 29 for receiving the similar hook portions of the member 19 of the connecting clamping mechanism. As a result of the construction described the members 19 and 20 may be 105 assembled in the position indicated in Fig. 5 with their hook portions engaging each other after which the bead of each member is brought into engagement with the corresponding insulator boss with the insulating 110 cushion material referred to in place and the members are tightly clamped in such position by means of the clamping screws extending through the halves of the members 19 and 20. This construction provides a 115 positive means for clamping each insulator by means of the mechanical clamping and connecting device without the use of cement and the construction may readily be given a strength equal to what the material of the 120 insulator 15 will stand. Furthermore the mechanical clamping and connecting mechanism by the cooperating hooks referred to, forms a flexible connection between the members of the clamp so that adjacent insulator units may have considerable swing 125 in any direction relatively to each other, which is desirable for supporting high tension conductors so that undue strains may not be brought to bear upon the insulator 130.

units by swaying of the supported conductors.

While it is desirable to have the insulator units of different diameter as referred to it will be understood that the bosses projecting from the insulators are preferably of the same size so that the connecting and clamping mechanism may all be of the same construction and size for any particular suspension system which materially simplifies and cheapens the cost of production.

The end insulating unit 18 as shown in Figs. 7 and 8 is provided with a modified form of clamping and supporting device for supporting the end of the antenna shown in Fig. 2. This clamping mechanism consists of a body portion 19^c forming one-half of a retaining cup, the other half of which is formed by a section 19^a held in position upon the body portion 19^c by two screws 30 when the parts 19^c and 19^a are held in clamping engagement with the boss of the insulator unit 18 by means of the screw 31. The edge of the cup referred to is provided with a bead for effecting the clamping engagement so that the insulator unit is rigidly secured to the clamping and supporting device, suitable insulating material of a cushioning nature being interposed between the bead and the boss in the same manner as above referred to. The body portion 19^c of the clamping device is provided on its outer surface with a ring 32 for engaging the end of the antenna and the outer surface of the body portion 19^c of the clamping device is provided with a shoulder 33 against which the shield 34 is held by the upper edge of the protecting cap 35, the latter being held in place on the body portion 19^c by a screw 36, access to which is afforded by an opening 37 formed through the shield 34. In connecting the antenna to the ring 32 the cap 35 is removed from its position indicated, the wire is passed through the ring 32 and the projecting end is twisted around the body of the wire and then the extending end of the wire is passed through the hole 38 provided in the side of the cap 35 to afford connection with the conductor extending to the operating instruments. The cap 35 is then moved to its position indicated in Fig. 7 and held in place by the screw 36. In connection with the entire construction it is desirable that all of the exposed edges and surfaces shall be rounded to avoid undue static discharge and this is readily accomplished by my construction of clamping devices since they are so related that it is not necessary at any place to have sharp edges or projecting points.

In using the suspension system for supporting a high tension electric line conductor, as for example the conductor 39 shown in Fig. 3, the suspension system is supported in any desired manner from a cross arm 40

as for example by an eye bolt 41 and the clamping mechanism at the lower end of the suspension is preferably modified as indicated in Figs. 9 and 10. The clamping mechanism shown in Fig. 9 is adapted to replace that shown in Fig. 7 and consists of two similar sections 42 and 42^a forming a cap construction substantially as above described in connection with Figs. 4, 5 and 6 held together by a clamping screw 43. The sections 42 and 42^a are provided with hook portions 44 and 44^a similar to those described in Figs. 4, 5 and 6, the principal difference being that these hook portions extend farther from the cup portions so as to receive a pin 45 shown in Fig. 10 for supporting the saddle 46 which saddle is in effect a curved trough having upwardly extending ears 47 through the upper ends of which the pin 45 passes. The saddle 46 is curved slightly so that the sag of the line wire 39 at its point of support will not damage the wire and make it liable to breakage.

While I have shown my invention in the particular embodiments above described it will be understood that I do not limit myself to the precise construction shown as I desire to cover by the appended claims any mechanical equivalents thereof known to the art at the time of the filing of this application.

What I claim is:

1. In combination, two insulators, each having a body portion and a projecting head and an annular groove between said body portion and said head and a transverse groove in the outer surface of said head, and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, said portions having bosses on their inner surface entering the ends of said transverse groove, insulating material clamped in each annular groove by the corresponding annular bead, each member having an inwardly dished end wall and the portions of each member having outwardly projecting overlapping transverse flanges provided with openings adjacent the center of the end wall of said member, whereby said overlapping flanges of each member may be disposed in the openings through the flanges of the other member, said flanges and end walls permitting a limited amount of motion of one member relatively to the other, said motion being limited by the engagement of the flanges of one member with the end wall of the other member.

2. In combination, two insulators, each

- having a body portion and a projecting head and an annular groove between said body portion and said head and a transverse groove in the outer surface of said head, 5 and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, said portions having bosses on their inner 10 surface entering the ends of said transverse groove, each member having an inwardly dished end wall and the portions of each member having outwardly projecting overlapping transverse flanges provided with 15 openings adjacent the center of the end wall of said member, whereby said overlapping flanges of each member may be disposed in the openings through the flanges of the other member, said flanges and end walls 20 permitting a limited amount of motion of one member relatively to the other, said motion being limited by the engagement of the flange of one member with the end wall of the other member.
3. In combination, two insulators, each having a body portion and a projecting head and an annular groove between said body portion and said head and a transverse groove in the outer surface of said head, 25 and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, said portions having bosses on their inner 30 surface entering the ends of said transverse groove, the portions of each member having outwardly projecting overlapping transverse flanges provided with 35 openings adjacent the center of the end wall of said member, whereby said overlapping flanges of each member may be disposed in the openings through the flanges of the other member.
4. In combination, two insulators, each having a body portion and a projecting head and an annular groove between said body portion and said head and a transverse groove in the outer surface of said head, 40 and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, said portions having bosses on their inner 45 surface entering the ends of said transverse groove, the portions of each member having outwardly projecting overlapping transverse flanges provided with openings adjacent the center of the end wall of said member, whereby said overlapping flanges of each member may be disposed in the openings through the flanges of the other member, said flanges and end walls permitting a limited amount of motion of one member 50 relatively to the other, said motion being limited by the engagement of the flange of one member with the end wall of the other member.
5. In combination, two insulators, each having a body portion and a projecting head and an annular groove between said body portion and said head and a transverse groove in the outer surface of said head, 55 and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, said portions having bosses on their inner 60 surface entering the ends of said transverse groove, the portions of each member having outwardly projecting overlapping transverse flanges provided with openings adjacent the center of the end wall of said member, whereby said overlapping flanges of each member may be disposed in the openings through the flanges of the other member, said flanges and end walls permitting a limited amount of motion of one member relatively to the other, said motion being limited by the engagement of the flange of one member with the end wall of the other member.

members, each of said members having an inwardly projecting annular bead for entering the annular groove in one of the insulators, each member consisting of two portions, a screw extending through said transverse groove and the portions of each member for clamping said portions together, said portions having bosses on their inner surface entering the ends of said transverse groove, the portions of each member having outwardly projecting overlapping transverse flanges provided with openings adjacent the center of the end wall of said member, whereby said overlapping flanges of each member may be disposed in the openings through the flanges of the other member.

5. In combination, two insulators, each having a body portion and a projecting head and an annular groove between said body portion and said head and a transverse groove in the outer surface of said head, and a mechanical connection between said insulators comprising two cup-shaped metal members, each of said members having an inwardly projecting annular bead for entering the annular groove in one of the insulators, each member consisting of two portions, a screw extending through said transverse groove and the portions of each member for clamping said portions together, the portions of each member having outwardly projecting overlapping transverse flanges provided with openings adjacent the center of the end wall of said member, whereby said overlapping flanges of each member may be disposed in the openings through the flanges of the other member.

6. In combination, two insulators, each having a body portion and a projecting head and an annular groove between said body portion and said head and a transverse groove in the outer surface of said head, and a mechanical connection between said insulators comprising two cup-shaped metal members, each of said members having an inwardly projecting annular bead for entering the annular groove in one of the insulators, each member consisting of two portions, a screw extending through said transverse groove and through the portions of each member for clamping said portions together, and overlapping hooks extending from the portions of each member for engaging the corresponding hooks on the other member.

7. In combination, two insulators, each having a body portion and a projecting head and an annular groove between said body portion and said head, and a mechanical connection between said insulators comprising two metal members, each of said members having an inwardly projecting annular bead for entering the annular groove in one of the insulators, each member consisting of two

- portions, a screw extending diametrically across each member and through the portions of each member for clamping said portions together, insulating material clamped 5 in each annular groove by the corresponding annular bead, each member having an inwardly dished end wall and the portions of each member having outwardly projecting overlapping transverse flanges provided 10 with openings adjacent the center of the end wall of said member, whereby said overlapping flanges of each member may be disposed in the openings through the flanges of the other member, said flanges and said 15 end walls permitting a limited amount of motion of one member relatively to the other, said motion being limited by the engagement of the flanges of one member with the end wall of the other member.

20 8. In combination, two insulators, each having a body portion and a projecting head and an annular groove between said body portion and said head, and a mechanical connection between said insulators comprising 25 two metal members, each of said members having an inwardly projecting annular bead for entering the annular groove in one of the insulators, each member consisting of two portions, a screw extending diametrically across each member and through the 30 portions of each member for clamping said portions together, each member having an inwardly dished end wall and the portions of each member having outwardly projecting 35 overlapping transverse flanges provided with openings adjacent the center of the end wall of said member, whereby said overlapping flanges of each member may be disposed in the openings through the flanges of the other member.

40 9. In combination, two insulators, each having a body portion and a projecting head and an annular groove between said body portion and said head, and a mechanical connection between said insulators comprising 45 two metal members, each of said members having an inwardly projecting annular bead for entering the annular groove in one of the insulators, each member consisting of two portions, a screw extending diametrically across each member and through the portions of each member for clamping said portions together, the portions of each member having outwardly projecting 50 overlapping transverse flanges provided with openings adjacent the center of the end wall of said member, whereby said overlapping flanges of each member may be disposed in the openings through the flanges of the other member.

55 10. In combination, two insulators, each having a body portion and a projecting head and an annular groove between said body portion and said head, and a mechanical connection between said insulators comprising two metal members, each of said members having an inwardly projecting annular bead for entering the annular groove in one of the insulators, each member consisting of two portions, a screw extending diametrically across each member and through the portions of each member for clamping said portions together, the portions of each member having outwardly projecting overlapping transverse flanges provided with openings adjacent the center of the end wall of said member, whereby said overlapping flanges of each member may be disposed in the openings through the flanges of the other member.

60 11. In combination, two insulators, each having a body portion and a projecting head and an annular groove between said body portion and said head, and a mechanical connection between said insulators comprising two metal members, each of said members having an inwardly projecting annular bead for entering the annular groove in one of the insulators, each member consisting of two portions, a screw extending diametrically across each member and through the portions of each member for clamping said portions together, and overlapping hooks extending from the portions of each member for engaging the corresponding hooks on the other member.

65 12. In a mechanical connection for two insulators in series arrangement, the combination of two cup-shaped members each having an inwardly projecting annular bead for entering an annular groove in one of the insulators and each consisting of two portions, a clamping screw extending diametrically across each member for clamping its portions together, and overlapping flanges projecting from the portions of each member and provided with openings for receiving the overlapping flanges of the other member.

70 13. In a mechanical connection for two insulators in series arrangement, the combination of two cup-shaped members each having an inwardly projecting annular bead for entering an annular groove in one of the insulators and each consisting of two portions, a clamping screw extending diametrically across each member for clamping its portions together, and overlapping flanges projecting from the portions of each member and provided with openings for receiving the overlapping flanges of the other member.

ceiving the overlapping flanges of the other member, the outer edges of said flanges of each member being adjacent the outer surface of the other member when said flanges are in engaged relation to limit the motion of one member relatively to the other.

14. In a mechanical connection for two insulators in series arrangement, the combination of two members each having an inwardly projecting annular bead for entering an annular groove in one of the insulators and each consisting of two portions, a clamping screw extending diametrically across each member for clamping its portions together, and overlapping flanges projecting from the portions of each member and provided with openings for receiving the overlapping flanges of the other member.

15. In a mechanical connection for two insulators in series arrangement, the combination of two members each having an inwardly projecting annular bead for entering an annular groove in one of the insulators and each consisting of two portions, a clamping screw extending diametrically across each member for clamping its portions together, and overlapping flanges projecting from the portions of each member and provided with openings for receiving the overlapping flanges of the other member, the outer edges of said flanges of each member being adjacent the outer surface of the other member when said flanges are in engaged relation to limit the motion of one member relatively to the other.

16. In combination, an insulator having a body portion, a projecting head, and an annular groove between said body portion and head, and a metal clamp having an inwardly projecting annular bead for entering said annular groove, said clamp comprising two portions, a screw extending diametrically across said insulator for holding the portions of said clamp in place on said

insulator, and supporting devices carried by said clamp.

17. In combination, an insulator having a body portion, a projecting head, and an annular groove between said body portion and head, and a metal clamp having an inwardly projecting annular bead for entering said annular groove, said clamp comprising two portions, a screw extending diametrically across said clamp for holding the portions thereof in place on said insulator, and supporting devices carried by said clamp, said insulator having a transverse groove across its head for receiving said screw.

18. In combination, an insulator having a body portion, a projecting head, and an annular groove between said body portion and head, and a metal clamp having an inwardly projecting annular bead for entering said annular groove, said clamp comprising two portions, a screw extending diametrically across said insulator for holding the portions of said clamp in place on said insulator, and supporting devices carried by said clamp, and sheet insulating material clamped between said annular bead and said annular groove.

19. In combination, an insulator having a body portion, a projecting head, and an annular groove between said body portion and head, and a metal clamp having an inwardly projecting annular bead for entering said annular groove, said clamp comprising two portions, a screw extending diametrically across said clamp for holding the portions thereof in place on said insulator, supporting devices carried by said clamp, said insulator having a transverse groove across its head for receiving said screw, and sheet insulating material clamped between said annular bead and said annular groove.

In witness whereof, I hereunto subscribe my name this 6th day of July, A. D. 1916.

EDSON O. SESSIONS.
